[57] CLAIM

The ornamental design for an combined audio and video amplifier, as shown and described.

DESCRIPTION

FIG. 1 is a perspective view of a combined audio and video amplifier showing my new design;

FIG. 2 is a front elevational view thereof;

FIG. 3 is a rear elevational view thereof;

FIG. 4 is a right side elevational view thereof, the left side view being a mirror image;

FIG. 5 is a top plan view thereof;

FIG. 6 is a bottom plan view thereof; and,

FIG. 7 is a perspective view thereof, the broken line showing of a remote controller with a crystal monitor is for illustrative purposes only and forms no part of the claimed design.
